US0D1094442S

(12) **United States Design Patent** (10) Patent No.: **US D1,094,442 S**
 Folken et al. (45) Date of Patent: ** Sep. 23, 2025

(54) **DISPLAY SCREEN OR PORTION THEREOF WITH GRAPHICAL USER INTERFACE**(71) Applicant: **Caterpillar Inc.**, Peoria, IL (US)(72) Inventors: **Keith Folken**, West Peoria, IL (US); **Mitchell B. Howard**, Lebanon, IN (US); **Mukund Jaganmohan**, Chennai (IN); **David Ochoa**, Boynton Beach, FL (US); **Bhaskara Rao Polisetty**, Nellore (IN)(73) Assignee: **Caterpillar Inc.**, Peoria, IL (US)(***) Term: **15 Years**(21) Appl. No.: **29/986,250**(22) Filed: **Jan. 17, 2025****Related U.S. Application Data**

(63) Continuation of application No. 29/854,050, filed on Sep. 21, 2022, now Pat. No. Des. 1,067,942, which is a continuation of application No. 29/830,154, filed on Mar. 10, 2022, now Pat. No. Des. 969,852, which is a continuation of application No. 29/798,488, filed on Jul. 8, 2021, now Pat. No. Des. 950,605, which is a continuation of application No. 29/759,396, filed on Nov. 23, 2020, now Pat. No. Des. 925,585, which is a continuation of application No. 29/714,839, filed on Nov. 26, 2019, now Pat. No. Des. 910,693, which is a continuation of application No. 29/659,224, filed on Aug. 7, 2018, now Pat. No. Des. 872,109.

(57)

CLAIM

The ornamental design for a display screen or portion thereof with graphical user interface as shown and described.

DESCRIPTION

The sole FIGURE shows a display screen or portion thereof with graphical user interface showing our new design. The peripheral dashed broken lines illustrate a display screen or portion thereof, and form no part of the claimed design.
